UNITED STATES PATENT OFFICE

2,001,671

PORTABLE ELECTRIC CURRENT TAP DEVICE

John Villa, Philadelphia, Pa., assignor to Max W. Bieberbach, Jr., Philadelphia, Pa.

Application September 3, 1932, Serial No. 631,661

1 Claim. (Cl. 177—311)

This invention relates to portable current tap devices designed for the connection of electric appliances such as vacuum cleaners, heaters, toasters, irons, etc.

5 In homes, offices and factories where appliances of the kind referred to are employed, the wall or floor outlets at which electric current is available are often inconveniently located, so that unduly long cords are necessary to reach from the outlets to the appliances requiring the current. Such long cords are objectionable in that they are cumbersome and therefore operate to restrict the free manipulation of appliances like electric irons for example.

10 My invention is directed in the main toward overcoming the above recited drawbacks through provision of a simple and compact portable tap device with facilities whereby it may be connected to a wall or floor outlet, which is capable of placement on a table or other support remote from the outlet, and which embodies receptacles for attachment of the conductor cords of the appliances, a switch whereby the electric current may be turned on and off, and a visual means to indicate flow of the current through the appliance.

15 Other objects and attendant advantages of this invention will be manifest from the detailed description following of the attached drawings whereof Fig. I shows a perspective view of my improved portable electric current tap device.

20 Fig. II is a plan view of the device with the top cover removed; and

Fig. III is a cross section taken as indicated by the arrows III—III in Fig. II.

25 As herein illustrated, my improved current tap device comprises a hollow rectangular box-like block 5 which is preferably made from a suitable di-electric material sufficiently heavy to resist displacement of the device when resting on a table or other support. Transversely arranged within the hollow of the block 5 are a snap switch 6; a socket mounting 7 for an incandescent current flow indicating bulb 8; and a double receptacle 9 for the prongs of the conductor plugs (not shown) of the appliances which are to be supplied with electric current. These elements 6, 7 and 9 may be of any standard or improved type, and, as shown in Figs. II and III, are secured by means of screws 10 to the lateral flanges 11a of an inner sheet metal lining casing 11. This casing 11 is designed to serve as a protection against fire hazards; and from Fig. III it will be noted that its lateral flanges 11a seat within longitudinal recesses 12 along the top of the block 5 and secured by screws 13.

30 As shown in Fig. I, the hollow block 5 is closed by a flush cover plate 15 which is formed with a slot for projection of the actuating lever 16 of the snap switch 6; an aperture with an inset jewel 17 directly over the incandescent current flow indicating bulb 8; and apertures through which the faces 18 of the double receptacle 9 are exposed, said cover being detachably fastened by screws 20 that take into metallic portions of the elements 6, 7 and 9.

35 To facilitate dissipation of the heat of the incandescent bulb 8, the hollow block 5 is provided in its opposite sides with escape apertures indicated at 21 in Figs. I and III. The flexible cord 22 through which the electric current is conducted to the tap device enters the block 5 by way of an opening at one end of the latter, and has its component leads 23 and 24, connected to the terminals of the switch 6. The cord 22 is in this instance fitted with a plug 25 capable of being screwed into a wall or floor outlet. The incandescent bulb 8 and the double receptacle 9 are suitably connected in circuit with the switch 6 by conductors not illustrated in the drawings.

40 From the foregoing it will be apparent that the tap device of my invention is serviceable as a means of current supply at a point remote from a wall or floor outlet for connection of electric appliances of various kinds. By virtue of its ready portability, the device can be placed on any suitable support in any position for convenient actuation of the snap switch 6 and for observation of the current-indicating incandescent bulb 8 at all times, by the operator. My invention thus makes possible the use of comparatively short conductor leads on the electric appliances so that the latter may be manipulated with the utmost freedom and ease and without liability of entanglement of said cords.

45 Having thus described my invention, I claim:

A portable electric current tap device comprising a block of combustible material having a longitudinal recess in one face thereof and having open grooves formed in the longitudinal walls thereof adjacent said recess, said block also having 45 ventilating apertures in the opposite longitudinal walls thereof, a unitary metal shield extending the entire length of said recess and having a depressed central portion co-extensive therewith and extending into said recess and spaced from the longitudinal walls thereof for purposes of ventilation, said shield having integral lateral flanges extending into the longitudinal grooves in said block and secured thereto, a manually operable switch device having metallic supporting 50 55

portions extending partially over the integral flanges of said shield and secured thereto, a socket mounting having metallic supporting portions extending partially over the integral flanges of said shield and secured thereto, a current flow indicating bulb in said socket mounting, an attachment receptacle having metallic supporting portions extending partially over the integral flanges of said shield and secured thereto, a cover plate adapted to fit over said block and secured to said metallic supporting portions of said switch de-

vice, said socket mounting and said attachment receptacle, said cover plate having spaced openings therein through which said switch device and said attachment receptacle are accessible and a jewel mounted thereon and through which said current flow indicating bulb is visible, and an electric cord connected to said switch device, said attachment receptacle and said socket and having means for connection to a wall outlet or other source of electric current. 5 10

JOHN VILLA.
